UNITED STATES PATENT OFFICE.

WILLIAM H. INSLEY AND ALVIN C. RASMUSSEN, OF INDIANAPOLIS, INDIANA, ASSIGNEES TO INSLEY MANUFACTURING COMPANY, OF INDIANAPOLIS, INDIANA, A CORPORATION OF INDIANA.

CONCRETE-HANDLING APPARATUS.

Application filed November 20, 1922. Serial No. 602,048.

To all whom it may concern:

Be it known that we, WILLIAM H. INSLEY and ALVIN C. RASMUSSEN, citizens of the United States, residing at Indianapolis, in the county of Marion and State of Indiana, have invented a new and useful Concrete-Handling Apparatus, of which the following is a specification.

This invention relates to improvements in apparatus for handling building material, especially concrete, and has particular reference to that type of apparatus wherein there is provided a mast or tower on which is supported a chute or chutes for delivering the material by gravity to the point desired, and on which operates an elevating bucket which raises the material to the desired height and then delivers the same to the chutes so that under the influence of gravity the material will be conveyed to the point of deposit.

One of the objects of our invention is to so construct an apparatus of the above character that the load on the mast will be so distributed and balanced as to reduce twisting and tilting strains on the mast to a minimum. Another object of our invention is to provide means whereby the vertical position of the bucket-discharging mechanism and the delivery chutes may be readily shifted to accommodate changing heights of structure. Another object of our invention is to provide means whereby the chute mechanism and the material delivery mechanism may be reversed as to position thus permitting of the delivery of the material over a wide range without any necessity of turning the mast which, in an apparatus of this character, is usually substantially secured at its base.

For the purpose of disclosing the invention, one embodiment thereof is illustrated in the accompanying drawings, in which

Fig. 1 is a front elevation of an apparatus embodying the invention;

Fig. 2 is a side elevation thereof;

Fig. 3 is an enlarged detail of the side elevation showing more fully the construction of the delivery apparatus and the mounting for the chutes;

Fig. 4 is an enlarged detail of the front elevation having particular reference to the delivery apparatus, and

Fig. 5 is a sectional view taken on the line 5—5 of Fig. 1.

In the construction illustrated, the mast or tower 1 as shown comprises four corner posts which are formed of angle iron, and diagonal braces which connect the angle iron posts together. The mast may be made in sections for convenience of transportation, the sections being joined together in erection by suitable joint plates 2. This mast is supported at its top by guy lines 3, and by guy lines 4 at suitable intermediate points depending upon the total height of the mast.

Near the upper end of the mast is provided a head-frame for supporting the chute hopper 5. This frame comprises a pair of horizontally disposed arms 6 extending forwardly from the mast and suitably braced by arms 7, the inner ends of which are secured to the mast and the outer ends of which are secured to the forwardly extending arms 6. Transversely of the arms 6 and therefore transversely of the mast are a pair of arms 8 which project beyond one side of the mast. At the outer ends of these arms 8 are a pair of vertically extending arms 9 secured to the arms 8 and suitably braced by plates 10 at their corners and by a brace 11 and bracing arm 12 along the side. The hopper 5 is secured to and supported by the lower ends of these arms to one side of the mast. Pivoted to the upper part of the hopper 5 are two pairs of links 13 and 14 the lower ends of which are pivoted to the bridge pan 15 of the hopper so that the bridge pan may be swung into or out of the hopper and at the same time maintain substantial parallel relation with respect to the bottom of the hopper.

The hoisting bucket for the material comprises a hopper bottom bucket 16 having a side delivery mouth 17 controlled by a pivoted gate 18 and adapted to deliver the concrete or other material to the chute hopper 5, the bridge pan 15 providing a bridge between the delivery end of the bucket and the hopper. The bucket is mounted on a traveling carriage 19 which travels vertically on the mast. This carriage at its lower end is provided with a pair of rollers or wheels 20 bearing on the front face of the two front angle posts of the mast and at its upper end

with a pair of wheels or rollers 21 engaging behind the angles of the front posts of the mast so that the frame and bucket will be guided in their vertical movement. The 5 bucket is elevated by a cable 22 operating over suitable sheaves 23 in the top of the mast and passing beneath a sheave 24 at the bottom of the mast to suitable hoisting apparatus 25. For tripping the gate 18 and 10 opening the same when the bucket reaches the limit of its upward travel a lever 26 is pivoted to the side of the bucket and connected by a cable 27 to the gate 18. At its 15 rear end it is adapted to engage a suitable stop 26' on the head-frame so that as the bucket reaches the limit of its movement the lever will be operated to open the gate. At 20 the same time the top of the bucket will engage a pivoted lever 28 connected by operating rods 29 with the bridge pan 15 and move the bridge pan beneath the delivery mouth 17 of the bucket. It will be noted that the delivery mouth 17 extends transversely of the bucket and the bucket thereby has a side 25 delivery instead of the ordinary front delivery, and that the hopper chute 5 and bridge pan 15 extend transversely to the mast so that the material from the bucket is delivered to one side of the mast instead of the 30 front of the mast as has heretofore been the custom.

On the rear of the mast there is provided a bracket 30 on which is pivotally supported a delivery chute 31. This chute on its under 35 side is provided with a pivot pin 32 suitably pivoted in a socket 33 on the bracket 30 so that the chute may be swung on this pivot to various positions. The outer end of the chute is supported by a boom-line 34 which 40 extends from the outer end of the chute to a bracket 35 secured at a point on the mast above bracket 30 and coinciding pivotally with pin 32. By this arrangement the pivot and supporting point of the inner end of 45 the chute and the upper end of the boom-line are brought well towards the mast so that twisting strains on the mast when the outer end of the chute is swung to one side or the other are substantially reduced. A 50 second chute 44, carried from and beneath the discharge end of chute 39, is customarily provided so that, by a combination of movements of the two chutes, any point within the circular area which they may describe 55 can be conveniently reached. Additional chutes may be used to extend the area of distribution.

It will be noted that the bucket and chute hopper are mounted on the front of the 60 mast and have a side or transverse delivery and that the conveyor chute is mounted on the rear of the mast with its receiving hopper 36 in close proximity to the mast. It will also be seen that the delivery end of the 65 chute hopper 5 is slightly beyond the side of

the mast. For conveying the material from the chute hopper 5 to the delivery chute 31 we provide a conveyor chute 39, the spout 40 of which is directly over the hopper of the chute 31 and the hopper 41 of which is beneath the hopper chute 5. The receiving end of the conveyor chute is supported from the hopper 5 by means of a bolt 42 secured in an angle 43 mounted on the hopper chute. The delivery end of the chute 39 is supported from the head 36 of chute 31. By reason of the fact that the elevating bucket 16 and hopper chute 5 have a side delivery the conveyor chute 39 may be made straight and short thereby avoiding turns or twists in the chute which would tend to obstruct the ready flow of the material.

The front and rear posts of the mast are provided with bolt holes 45 which are regularly spaced throughout the height of the mast an equal distance apart. These holes are provided for securing to the front face of the mast the head-frame or bucket-discharging mechanism and its associated parts, and to the rear face of the mast the chute 90 supporting brackets.

The spacing of the bolt holes in the parts constituting the head-frame and the chute supporting brackets is the same as the spacing of the holes in the mast. This arrangement provides means whereby the head-frame on one side and the chute-supporting brackets on the other may be secured to the mast at any vertical height desired and also whereby the parts may be reversed from one side of the mast to the other. Due to the fact that the traveling frame support for the bucket may be readily disconnected from the mast and the rear mast posts are the same as the front mast posts the bucket likewise may be transposed from either side of the mast to the other. By this arrangement delivery may be made to any point within the periphery of a circle having the mast as its center and described by the combined length of the chutes as a radius and at any height within the vertical range of the mast.

While the terms "front" and "rear" have been applied to certain sides of the mast, these terms have been used for the purpose of clearness rather than for indicating the fact that the apparatus has an actual front and rear. The terms therefore, where used in the specification and claims must be considered merely in a relative sense.

We claim as our invention:

1. An apparatus for handling building material comprising a mast, a chute hopper carried by said mast on the front thereof and projecting beyond the vertical plane of said front, an elevator bucket carried by said mast on the same side as said chute hopper, and a delivery chute carried on the rear of said mast and arranged to receive material from said chute hopper.

2. An apparatus for handling building material comprising a mast, a chute hopper carried by said mast on the front thereof and projecting beyond the vertical plane of said front, an elevator bucket carried by said mast on the same side as said chute hopper, a delivery chute carried on the rear of said mast and a conveyor chute extending between said delivery chute and chute hopper. 50
- 10 3. An apparatus for handling building material comprising a mast, a chute hopper carried on the front of said mast and arranged to deliver material towards one side of said mast, an elevator bucket carried by said mast having a side delivery for cooperating with said chute hopper, a delivery chute supported on said mast with its weight acting on said mast in opposition to the weight of the chute hopper and bucket and 55 means for delivering the material from said chute hopper to said conveyor chute. 60
- 15 4. An apparatus for handling building material comprising a mast, a chute hopper supported on the front of said mast and projecting beyond the vertical plane of said front, an elevator bucket mounted on said mast on the same side as said chute hopper, a swinging conveyor chute pivotally supported on the rear of said mast with its 65 weight acting in opposition to the weight of said hopper and bucket and having its pivoted end in close proximity to the mast, and means for delivering the material from said chute hopper to said conveyor chute. 70
- 20 5. An apparatus for handling building material comprising a mast, a chute hopper supported on the front of said mast and having its delivery end at the side of and beyond said mast, an elevator bucket mounted on said mast, a conveyor chute supported on said mast in balancing relation with respect to said bucket and chute hopper, and an intermediate chute extending from the 75 delivery end of said chute hopper to said conveyor chute. 80
- 25 6. An apparatus for handling building material comprising a mast, an elevator bucket mounted on the front of said mast for vertical movement thereon, the mast and bucket having inter-engaging parts which leave the portion of the mast between the front and rear free for attachment of guy wires at intermediate points while permitting a vertical movement of the bucket, a chute hopper mounted on the front of the mast and having its delivery end extending toward and beyond one side of the mast, a delivery chute mounted on said mast on the rear of the mast and in balancing relation with respect to the chute hopper and a transfer chute extending from said chute hopper to said conveyor chute. 85
- 30 7. An apparatus for handling building material comprising a mast having bolt receiving openings spaced at regular intervals on its front and rear throughout its height, a chute hopper supporting frame arranged to be mounted on either side of said mast and at any height and having bolt receiving portions spaced to cooperate with said bolt receiving openings on the mast, a bucket arranged for vertical movement on either side of said mast for cooperating with said chute hopper, a delivery chute support having bolt receiving portions spaced to cooperate with the spacing of the bolt openings and arranged for mounting on either side of the mast and at any height, said support being mounted on the side of the mast opposite to that of the bucket and chute hopper and at a proper height in relation to the chute hopper, a delivery chute mounted on said support and means for conveying the material from said chute hopper to said delivery chute. 90
- 35

In witness whereof, we have hereunto set our hands at Indianapolis, Indiana, this 9th day of November, A. D. one thousand nine hundred and twenty-two.

WILLIAM H. INSLEY.
ALVIN C. RASMUSSEN.
